UNITED STATES PATENT OFFICE.

VICTOR KAPLAN, OF BRÜNN, AUSTRIA.

TURBINE-MACHINE.

1,399,059.

Specification of Letters Patent.

Patented Dec. 6, 1921.

Application filed November 26, 1913. Serial No. 803,334.

To all whom it may concern:

Be it known that I, VICTOR KAPLAN, of Brünn, in the Empire of Austria, have invented certain new and useful Improvements in Turbine-Machines, of which the following is a specification.

My invention relates to turbine machines of the kind generally employed as water turbines, steam or gas turbines, rotary 10 pumps or centrifugal blowers.

The principal object of my invention is to provide a turbine machine working with high efficiency even if the specific speed of the runner wheel is greater than that hitherto used. A further object of my invention is to provide a turbine machine of strong construction, which is enabled to run at the highest possible speeds without getting in danger of being disturbed by the influence of centrifugal forces or the pressure of the fluid. A further object of my invention is to increase the efficiency of such a class of water turbines so far used and called "high speed runners."

These results are obtained by reducing the friction losses caused by the flow of fluid passing through the runner wheels, also by discharging the fluid along the lower or base edges of the guide vanes and also by accommodating the meridional flow of fluid from the entrance to the discharge end of the turbine machines to the natural flow of fluid, not being forced to change its direction by means of specially curved guide surfaces, 35 but only by a free deflection as it is herein-after fully pointed out.

With these and other objects in view, as will more fully hereinafter appear, my invention consists of certain novel features of construction and arrangement of guide and runner wheels for turbine machines above mentioned, hereinafter fully described, illustrated in the accompanying drawings and particularly pointed out in the appended 45 claims.

In the accompanying drawings:

Figure 1 is a vertical section through the left hand half of the guide wheel and the runner of a water turbine in accordance 50 with my invention.

Fig. 2 is a plan view of the turbine, the guide-wheel-cover being removed.

Fig. 3 is a vertical section of the left hand half of a twin turbine according to my invention.

Fig. 4 is a vertical section through the left hand half of a modified form of a water turbine hereinafter particularly described.

Fig. 5 is a vertical section through the left hand half of a twin turbine.

To explain clearly the drawings it will be noticed that in Figs. 1, 3, 4 and 5 the guide vanes S_1 and the runner blades S_2 are sketched in a radial projection. Referring to the drawings, the turbine machine 60 has connected to it a guide-wheel which may be constructed in the general manner as known in similar constructions for conducting and guiding the driving means to the rotor wheel. But a special arrangement 65 shows the guide vanes, the lower or base edges of which project over the wall of the suction pipe and if required may be extended in close proximity to the axis. To explain the term, "base or lower edges" it 70 may be stated that the guiding surface of a guide blade S_1 (Fig. 1) is circumscribed by two axial or nearly axial edges a_4, a_4 and a_1, a_1 hereinafter referred to as "inlet and outlet edges" and by the base or lower edge 75 (a_2, a_2) and the top or upper edge (a_3, a_3) . In the usual constructions the lower and top edges have not been utilized for allowing a smooth flow of fluid into the runner wheel, on the contrary a smooth discharge of the 80 fluid along said edges of the guide vanes is a characteristic feature of my invention. For this purpose the base edges project over the wall of the suction pipe T and also discharge the fluid without shock into the 85 runner wheel. In spite of this, these lower and top edges will not be called "outlet edges." This definition shall be reserved only for the axial or nearly axial edges of 90 radial discharging guide blades as has been 95 customary hitherto.

Figs. 1 and 2 show a guide wheel or distributor comprising a series of guide vanes S_1 of the described kind, each on a fixed pivot D (Fig. 1), the upper end of which, 100 being threaded, extends upward through the cover E , the lower end of such pivots extending downward through the horizontal flange of the suction tube T near the governing ring R .

The process of governing by means of movable guide vanes is the same as hitherto used in similar regulating contrivances. But the described arrangement of the guide vanes S_1 allows the discharge of fluid not 110

only along the outlet edges a_1 a_1 but also along the lower edges a_2 a_2 .

Fig. 3 is a modification of said guide wheel adapted for a twin wheel. Both the upper 5 or top edges a_3 a_3 and the lower edges a_2 a_2 and also the outlet edges a_1 a_1 of the guide vanes S_1 discharge the fluid into the rotor wheel.

Figs. 4 and 5 show a further modification 10 of a guide wheel, the guide vanes S_1 thereon extending near the turbine shaft. If a single runner wheel is employed, as seen in Fig. 4 the whole quantity of fluid or the main portion of the same is discharged from 15 the lower edges a_2 a_2 , of the guide vanes S_1 .

But if a twin runner wheel is employed as shown in Fig. 5 the whole quantity or the main portion of fluid is discharged both from the lower edges a_2 a_2 and from the upper 20 edges a_3 a_3 of said vanes. By such a modified form of a distributor it is not difficult to arrange the guide blade bolts near the turbine shaft as it is sketched in Fig. 4 but I do not limit my invention, to the above 25 mentioned guide vanes extending near the turbine axis because also guide vanes projecting only slightly over the wall of the suction pipe in connection with runner wheels hereinafter described in detail and shown 30 in Figs. 1, 2, 3, 4 and 5 give also satisfactory results.

The runner consisting of a series of runner blades S_2 rigidly fastened into the wheel-cover plate P (Figs. 1 and 3) or into 35 the nave N (Figs. 4 and 5) is located at a convenient distance below the lower edges of the guide vanes S_1 . A characteristic feature of my invention is the form of said wheel. Fig. 1 shows a general arrangement 40 thereof.

The runner blades S_2 forming spaces R_1 and R_2 between each other, the one set of runner spaces (R_2) adapted for an axial or nearly axial admission, and the other set of 45 spaces (R_1) adapted for a radial or nearly radial admission. For this purpose the inlet edges e_2 e_2 of the axial flow runner blades R_1 are arranged more or less in the proximity of the lower edges a_2 a_2 of the guide 50 vanes S_1 , while the inlet edges e_1 e_1 of the radial flow runner blades R_1 are arranged more or less in the proximity of the outlet edges a_1 a_1 of the guide vanes. In order to explain clearly the object of my invention I 55 have indicated in Fig. 1 by the dotted lines L an imaginary intermediate wall forming an imaginary outer wheel rim for the runner spaces R_1 and an imaginary inner wheel rim for the runner spaces R_2 . It will be 60 seen that by such an imaginary division, a runner wheel of my invention is sub-divided into two well-known turbine wheels. The one type of which with the blade spaces R_1 approximately corresponds to a normal speed 65 runner of a Francis turbine, while the other

type with the blade spaces R_2 nearly resembles an axial flow runner hitherto used under the name of "Jonval runner wheel".

For the satisfactory working of the turbine machine it is important to state that the 70 principal aim of the wheel construction is directed by a suitable enlargement in the radial breadth B of the axial flow runner spaces R_2 for obtaining the aforesaid free deflection of the fluid. For this purpose the 75 runner diameter D_2 of the outer wheel rim K is so far increased in relation to the diameter D_1 of the radial flow runner spaces R_1 that the quantity of fluid admitted to the axial portion of the runner wheel is greater 80 than that admitted to the radial portion of said wheel.

In opposition to the constructions of high speed runners hitherto used which are adapted chiefly for a radial admission (Francis- 85 turbine-wheels), a high speed runner of my invention is chiefly adapted for an axial admission. Still it must be specially stated that the aforesaid radial runner spaces R_1 form only a connecting link between my invention and the high-speed runner wheels hitherto used, and if necessary may be also quite dispensed with as is shown in Figs. 4 and 5. By such an arrangement the runner wheel is provided only with axial flow 90 blades extending from the runner nave N toward the wall of the suction pipe T . The entrance edges e_2 e_2 of said blades are located at a convenient distance below the lower edges a_2 a_2 of the guide vanes S_1 . 100

Although the runner wheel in its form approaches a combination of two well-known forms of water turbine wheels (axial flow and Francis-wheels) or resembles simply an axial flow wheel, there is however a distinct 105 difference in the method of the water supply needed for a wheel hitherto used, and one of my invention.

In an axial flow wheel of the usual construction the water flows through the guide wheel chiefly in an axial direction. In my invention however, the main portion of fluid enters the guide wheel in a radial direction and is freely deflected in the guide spaces, and flows in an axial or nearly axial direction into the runner wheel. The accompanying drawings show this new method of the flow of fluid in various modified forms. 110

Figs. 1 and 2 show the arrangement of a guide wheel and a runner wheel, the latter 120 consisting of a combination of an axial and a radial flow runner wheel. The water entering centripetally between the guide vanes S_1 is freely deflected in the guide vane spaces and its main portion flows in an axial or 125 nearly axial direction, (indicated by the arrows 2) into the axial flow runner spaces R_2 . Only a smaller portion of fluid has not been materially deflected and flows in nearly the same radial direction (indicated by the ar- 130

rows 1) into the radial flow runner spaces R_1 . The fluid having transferred its driving power into the runner wheel, flows off through the suction tube T to a waste-channel.

- In order to increase the quantity of water needed for the turbine machine, I have constructed a twin turbine as is shown in Fig. 3. The twin runner wheel of such a turbine consists generally of a doubling of the aforesaid runner wheel (Fig. 1). Opposite to the blade space R_2 , there is an identical or nearly identical blade space R_3 . The water entering the guide wheel in a radial direction is freely deflected between the guide vanes thereon and flows not only along the lower edges a_2 and a_2' and the outlet edges a_1 and a_1' but also along the upper edges a_3 and a_3' into the runner wheel as indicated by the arrows 3.
- If the whole quantity of water entering the guide wheel is to be deflected from its radial entrance direction for the purpose of an axial or nearly axial inlet into the runner wheel, the runner wheel should have single blade spaces R_2 as shown in Fig. 4. The free deflection of the water in the guide spaces is indicated by the arrows 2.

But I do not limit my invention to the guide vanes extending near the turbine shaft 30 and indicated in Fig. 4 because guide vanes projecting only slightly over the wall of the suction tube in connection with a runner wheel of the above description give also satisfactory results. In such a case the water 35 leaves the guide vanes also along the outlet edges and its free deflection is continued in the clearance between the guide vanes and the runner blades.

A runner wheel indicated in Fig. 4 may be 40 also doubled, if the supply of water is much increased.

Fig. 5 shows such a twin turbine. The guide wheel of which discharges the water both along the lower edges a_2 and a_2' and the 45 upper edges a_3 and a_3' as indicated by the arrows 2 and 3. For this purpose two runner spaces R_2 and R_3 adapted for an axial or nearly axial admission are arranged near said edges. It is evident, that a satisfactory 50 working may also be obtained by the arrangement of guide vanes projecting only slightly over the wall of the suction pipe as is clearly explained above.

In order to make clear the importance of 55 the axial runner spaces it may be explained, that only by the arrangement of such spaces a free deflection of the radial flow of fluid is to be obtained, as can be seen from the following explanation.

If the runner wheel and the guide wheel 60 of a water turbine are both removed it is proved by hydraulic experiments that the major portion of the water entering the suction tube flows to the tube in a radial or 65 nearly radial direction, without (as sup-

posed above) being forced to this radial inflow by an arrangement of special guide surfaces. Nevertheless the flow through the tube is in an approximately axial direction.

For this reason it is evident that this natural flow of fluid should be interrupted as little as possible. But this natural flow of fluid should not be disturbed by a special curvature of the wheel cover plate P as hitherto employed. In my invention this requirement is supplied by the aforesaid arrangement is axial flow runner spaces R_2 (Figs. 1, 2, 3, 4 and 5), which are so enlarged in their radial breadth that the major portion or the whole quantity of fluid can flow 80 through the said spaces, and therefore the wheel-cover plate P (Figs. 1 and 3) can be so much reduced in its radial extension, that its form and curvature do not influence the above mentioned natural flow of fluid 85 through the turbine machine. Moreover by such an arrangement of axial flow runner spaces, the inlet of fluid into the runner wheel is also facilitated, because the guide vanes are thus enabled to project materially 90 over the wall of the suction pipe. For this reason such vanes discharge the water also along their lower edges into the runner wheel. It is not difficult to provide such a curvature of the lower edges of the guide vanes that 95 the fluid admitted to the axial flow runner spaces can flow into said spaces without eddies and shock.

By the theory of three-dimensional flow it is found to be advantageous if the outlet 10 angles of the guide vanes are accommodated to the natural flow of fluid. But it has not been possible to carry out this condition hitherto, because the angles along the outlet edges cannot be increased toward the lower 105 edges, as required by the aforesaid theory because in such a case the guide vanes, if movable in the usual manner, could not be closed entirely. In my invention however the curvature of the lower edges a_2 and a_2' and 110 the size of the outlet angles thereof can be accommodated to a smooth inflow (without shock) into the axial runner spaces, as is shown in Fig. 2. Nevertheless the closing of the guide passage is complete even if the 115 guide vanes are movable in the usual manner. A further advantage obtained by such a combination consists in reducing the loss by friction of fluid caused by the runner blades and the wheel cover plate P. If said 120 parts rotate at a high speed, it is evident that said losses are as much increased as the relative velocity between the guide surfaces and the flowing fluid is accelerated, and therefore these parts of guide surfaces rotating at a considerable distance from the 125 turbine axis cause the greatest losses by friction. In order to reduce said losses I have transferred in the manner above described the radial flow runner spaces R_1 in 130

close proximity to the turbine shaft, because in the neighborhood of said shaft the relative velocity between the guide surfaces and the flowing fluid is slight even with a high 5 number of revolutions of the runner wheel. It will be seen from Fig. 1 that by such an arrangement only the outermost portions of the axial flow runner spaces R_2 are influenced by a great relative velocity, while 10 the radial flow spaces in their full axial extension lie in a zone of much reduced relative velocity. For this reason the friction of fluid caused by the wheel cover plate P (Fig. 1) is also reduced, because its outer 15 diameter can be thus diminished. A further reduction of said friction losses can be obtained by nearly or completely removing the radial runner spaces R_1 as will be seen from Figs. 4 and 5. By such arrangement 20 therefore the wheel cover plate shrinks to a runner nave N , and it is evident that the friction losses caused by such a nave are still more reduced.

Another advantage of the above described 25 arrangement is that it provides a runner wheel of a strong construction. It is evident that the runner blades running at very high speed are much affected by the centrifugal forces. Any tendency to alter the form of 30 said blades by the influence of such forces will best be counteracted by extending said blades in a radial or nearly radial direction. An arrangement of this kind requires generally a series of axial flow runner blades and 35 for this purpose a runner wheel adapted for an axial or nearly axial admission indicated by the Figs. 4 and 5 is enabled to run at the highest possible specific speed, without getting in danger of being disturbed by the 40 influence of centrifugal forces. Although the wheel construction of high speed runners hitherto used shows a radial or nearly radial admission, I have shown by the above mentioned reasons and tested by hydraulic 45 experiments that the efficiency and the specific speed of a runner wheel chiefly adapted for an axial admission and provided with a free deflection of water flow is superior.

It will be well understood that various 50 changes in the form, proportions, size and minor details of the structure of my invention may be made without departing from the spirit, or sacrificing any of the advantages above described.

55 In the specific examples illustrated I have shown a series of water turbines in their most simple form, comprising a guide wheel which resembles the construction of a distributor for Francis turbines. The guide 60 vanes thereon movable in the usual manner and their edges sketched in the radial projection as straight lines. But guide vanes rigidly fastened in the turbine casing give also satisfactory results even if the edges of 65 the guide blades are curved. Also it is gen-

erally not necessary to shape the entrance edges e_1, e_2 of the axial flow runner blades as a straight line extending in a radial direction from the nave toward the suction tube, as is indicated by Fig. 5. It will be seen 70 from Fig. 4 that said edges also may be curved as long as the main portion of water is still admitted in a nearly axial direction. Such a curvature of the entrance edges therefore should be adopted, if the turbine wheel 75 works under a high pressure of water. It is evident, that in such a case these parts of runner blades adjacent to the runner nave are under much stress due to bending from water pressure. In such cases I prefer to 80 increase the axial breadth of the runner blades toward the runner nave by curving the entrance edges thereon upward and toward said nave. Also the form and curvature of the guide wheel cover E (Figs. 1 85 and 4) have no influence on the good working of the turbine machine, so long as the free deflection of water is not disturbed. A water turbine with a guide wheel and a runner 90 wheel of the kind described, may be utilized everywhere and particularly for high specific speeds. It is well known, that many water-courses cannot be utilized for the reason, that the number of revolutions is too small, and low specific speeds require 95 expensive machinery and buildings. By the use of my invention however the erection of a turbine plant is economical, even if the employment of high speed runners of the form hitherto used in the construction of such 100 plant would be too expensive.

Having ascertained the advantages obtained by adopting axial flow runner spaces of the kind described it is evident, that such a combination of a distributor and a runner 105 wheel can also be utilized for steam and gas turbines, if the guide and runner spaces are accommodated to the gaseous nature of the driving agent.

While I have described my invention as 110 applied to prime movers, it will be understood that I do not consider it to be limited thereto, but contemplate applying it to pumping apparatus also.

Having thus fully described my invention, 115 what I claim as new, and desire to secure by Letters Patent is—

1. In a turbine machine the combination of a guide wheel, the guide vanes thereon projecting over the wall of the suction pipe, 120 and a runner wheel comprising a series of runner blades forming spaces between each other, the one set of runner spaces adapted chiefly for an axial admission and arranged near the lower edges of the guide blades, the 125 other set of runner blades adapted chiefly for a radial admission; the fluid entering the guide wheel centripetally being freely deflected between the guide vanes, and the quantity of fluid admitted to the axial por- 130

- tion of runner wheel being greater than the quantity admitted to the radial portion of said wheel.
2. In a turbine machine the combination of a guide wheel, the guide vanes thereon projecting over the wall of the suction pipe, and a runner wheel comprising a series of runner blades, forming spaces between each other, one set of said runner spaces adapted chiefly for an axial admission and arranged near the lower edges of the guide vanes, another set of axial flow runner spaces arranged near the upper edges of said guide vanes and a third set of runner spaces adapted chiefly for a radial admission, the fluid entering centripetally between the guide vanes being freely deflected in the guide spaces and the quantity of fluid admitted to the axial portion of the runner being greater than the quantity admitted to the radial portion of said wheel.
3. In a turbine machine, the combination of a guide wheel, the guide vanes thereon projecting over the wall of the suction pipe, and a runner wheel comprising a series of runner blades forming spaces between each other adapted for an axial or nearly axial admission and arranged near the lower edges of the guide vanes, the fluid entering centripetally between the guide vanes being freely deflected in the guide spaces and flowing in an axial or nearly axial direction into the runner wheel.
4. In a turbine machine, the combination of a guide wheel, the guide vanes thereon projecting over the wall of the suction pipe, and a runner wheel comprising two sets of runner blades forming spaces between each other, adapted chiefly for an axial admission, the one set arranged near the lower edges of the guide vanes and the other set arranged near the upper edges of said vanes, the fluid entering centripetally between the guide vanes being freely deflected in the guide spaces and flowing in an axial or nearly axial direction into the runner wheel.
5. In a turbine machine the combination of a distributor for Francis turbines, and a runner wheel comprising a hub and a series of axial-flow blades arranged around said hub and rigidly secured therein extending in a direction the major component of which is radial toward the wall of the suction pipe, the guide vanes projecting over the wall of said suction pipe the lower edges and the outlet edges of said vanes being open to the runner wheel and discharging the fluid into the runner blades.
6. In a turbine machine a runner wheel forming a combination of a Francis wheel and an axial-flow wheel, the quantity of fluid admitted to the axial portion of the runner being greater than the quantity admitted to the Francis wheel, a guide wheel for Francis turbines provided with guide

vanes, projecting over the wall of the suction pipe, the lower edges and the outlet edges of said vanes being open to the runner wheel and discharging the fluid into the runner blades.

7. In a turbine machine the combination of a distributor for Francis turbines, the guide vanes thereon projecting over the wall of the suction pipe, and a runner wheel comprising a hub, two series of axial or nearly axial-flow blades arranged the one near the lower and the other near upper edges of the guide blades and rigidly secured into the runner hub, the lower, the upper and the outlet edges of said blades being open to the runner blades and discharging the fluid into the runner wheel.

8. In a turbine machine a runner wheel forming a combination of a Francis wheel and two axial-flow wheels, the one arranged near the lower edges of the guide vanes, and the other near the upper edges of said vanes, a distributor for Francis turbines, the guide vanes thereon projecting over the wall of the suction pipe, the quantity of fluid admitted to the axial portions of the runner wheel being greater than the quantity admitted to the radial portion of said wheels.

9. In a turbine machine the combination of an impeller and a guide wheel, the former consisting of a hub and a series of axial-flow blades arranged around said hub and rigidly secured therein extending in a direction the major component of which is radial toward the wall of the suction pipe, and the guide vanes projecting over the wall of said suction pipe, the fluid flowing through the impeller chiefly in an axial direction, is freely deflected to the guide spaces, and leaving the guide wheel in an axial or nearly axial direction.

10. In a turbine machine the combination of a guide wheel, the guide vanes thereon projecting over the wall of the suction pipe, and an impeller comprising a series of impeller blades forming spaces between each other, the one set of impeller blades adapted chiefly for an axial flow and arranged near the lower edges of the guide blades, the other set of impeller blades chiefly adapted for a radial flow, the quantity of fluid discharged to the axial portion of the impeller being greater than the quantity discharges to the radial portion of said impeller.

11. In a turbine machine the combination of a guide wheel, the guide vanes thereon projecting over the wall of the suction pipe, and an impeller comprising a series of impeller blades forming spaces between each other, one set of said impeller spaces adapted chiefly for an axial flow and arranged near the lower edges of the guide vanes, another set of axial flow impeller spaces arranged near the upper edges of said guide vanes, and a third set of impeller spaces adapted

chiefly for a radial flow, the quantity of fluid discharged to the axial portion of the impeller being greater than the quantity discharged to the radial portion of said impeller.

- 5 12. In a turbine machine the combination of a guide wheel, the guide vanes thereon projecting over the wall of the suction pipe, and an impeller comprising a hub, two series 10 of chiefly axial flow blades arranged near the lower and the upper edges of the guide vanes, and rigidly secured into the impeller hub, the fluid flowing through the impeller chiefly in an axial direction being freely deflected 15 into the guide spaces and leaving the guide wheel in an axial or nearly axial direction.

13. In a turbine machine, the combination 20 of guide blades, and runner blades forming spaces between each other contiguous to the radial edges and to the axial edges of said guide blades, the spaces contiguous to the radial edges being relatively large whereby the passage of the greater part of the motive fluid takes place between the radial edges, 25 said guide blades and runner blades being so arranged that the direction of flow changes freely from either the radial to the axial or the reverse according to the direction of flow.

14. A turbine machine comprising in combination 30 a runner provided with axial flow blades, guide blades arranged to extend in a generally radial direction with respect to the axis of said runner and extending from the

outer edges of the runner blades toward the axis of the runner, the radial edges of the 35 guide blades being open to the runner blades and contiguous thereto whereby the fluid is free to change its direction in the guide space in passing through the machine, said guide blades being curved in the radial direction 40 whereby the fluid passes through the machine without shock.

15. A turbine machine comprising in combination a runner provided with axial flow blades, guide blades arranged to extend in a 45 generally radial direction with respect to the axis of said runner and extending from the outer edge of the runner blades toward the axis of the runner, the lower edges of the 50 guide blades being open to the runner blades and contiguous thereto whereby the fluid is free to change its direction in the guide space in passing through the machine, said guide blades being so formed as to present cylindrical surfaces to the fluid, the elements of 55 said cylindrical surfaces being parallel to the axis of the runner and the blades being curved in the radial direction whereby fluid passes through the machine without shock.

In testimony whereof I have signed this 60 specification in the presence of two subscribing witnesses.

VICTOR KAPLAN.
